UNITED STATES PATENT OFFICE.

JOHN J. COOPER, OF NEW YORK, N. Y.

LEG AND FOOT DEVELOPER.

Application filed September 23, 1924. Serial No. 739,387.

To all whom it may concern:

Be it known that I, JOHN J. COOPER, a citizen of the United States of America, and a resident of the city of New York, borough 5 of Manhattan, in the county and State of New York, have invented a new and Improved Leg and Foot Developer, of which the following is a description.

My invention relates to a surgical appliance and particularly to an appliance that will be effective in restoring lost functions to certain important muscles of the hips, legs and feet.

Many muscles become atrophied or essentially without function, owing to the lack of proper exercise or by reason of disease or wounds, and the prime object of my invention is to provide an appliance embodying elements constituting in effect artificial ligaments which will so function as to subject the muscles and tendons of the hips, legs and feet to a resistance in walking to bring about a control of defective muscles and act in a compelling manner on the person being treated and in a way to activate the muscles and restore them to normal functions as well as to produce proper blood circulation in the affected regions.

Another object in view is to produce an appliance corrective of leg and foot defects without the employment of splints or arch supports as usually employed.

It is recognized by orthopedists and other surgical practitioners as well as by those engaged in the correction of physical defects, that straight heel and toe walking and walking by toeing in aid in preventing a tendency to develop fallen arches and flat feet and that said heel and toe walking and toeing in will go far to restore and correct fallen arches and flat feet by activating the muscles and tendons of the feet and bringing about ample blood circulation in the feet particularly at the arches. Accordingly, it is an object of my invention to provide an appliance that will make heel and toe walking and more or less of a toeing in in walking natural and normal and in fact be compelling toward a practice of the corrective walking referred to.

Specifically, the invention has for its object to provide an appliance for the stated purpose characterized by few parts of simple form and arrangement which may be conveniently worn by male or female subjects requiring treatment in the directions re-

ferred to, and which is characterized as well by a convenient adjustability so that the appliance may be employed in the most effective manner and in a way offering 60 muscle resistance along lines calculated to produce the maximum restorative effects on the parts or areas requiring correction and restoration, to a degree approaching or attaining normalcy.

In a practical embodiment of my surgical appliance having elongated resilient elements constituting ligaments, means is provided to hold the ligaments at the upper ends and advantageously the said means is 65 in the form of a waist belt having a device adapted for attachment to an article of wearing apparel to prevent displacement of the belt vertically or in a direction about the body; and also at the lower ends the 70 ligaments have means to secure the same to the shoes of the wearer or to an equivalent anklet or other article of wear. Furthermore in the practical carrying out of the invention, guide means is preferably provided 75 for the ligaments between the upper and lower ends thereof to directionally determine the pull for a completely effective action by the ligaments.

Reference is to be had to the accompanying drawings forming a part of this specification, it being understood that the drawings are merely illustrative of examples of the invention.

Figure 1 is a perspective view of a leg 90 and foot developer embodying my invention, showing the same in use;

Figure 2 is an elevation of the leg and foot developer before application to the person to be treated;

Figure 3 is a detail in enlarged transverse vertical section as indicated by the line 3—3, Figure 2;

Figure 4 is a vertical section taken through one of the clasps for attaching the lower end 100 of the ligament to the top of the shoe upper or equivalent article of wear;

Figure 5 is an elevation of a leg band or garter equipped with guide means for the ligament in accordance with my invention;

Figure 6 is a fragmentary view in elevation of a modified belt attachment adapted to be engaged with corset strings when the developer is worn by a woman;

Figure 7 is a view similar to Figure 4 but 110 showing a modified form of clasp;

Figure 8 is a perspective view illustrat-

ing a modification employing an anklet and foot strap as a foot sling instead of using the shoe as a foot sling;

5 Figure 8^a is an enlarged perspective view of the anklet and foot strap assemblage shown in Figure 8, the view including a fragment of the ligament element;

Figure 9 is a detail in vertical section on line 9—9, Figure 8^a;

10 Figure 10 is a fragmentary view in elevation to be further referred to;

Figure 11 is a perspective view illustrating a modification of the anklet assemblage;

15 Figure 12 is a perspective view similar to Figures 1 and 8 illustrating an adaptation of the appliance for juvenile wear.

In carrying out my invention in accordance with the illustrated example a broad belt 10 is provided, adapted to be worn 20 about the waist. Pendent from the belt 10 are elongated elements designated generally by the numeral 11 and hereinafter referred to further, said elements constituting ligaments, as will appear. At the lower ends the ligaments are provided with clasps 12 and as 25 the strains on the ligaments are more or less severe, it is important to effect a firm holding by the clasp 12 for which purpose as shown in Figure 4 the lever 13 on the 30 clasp is adapted to bind against the outer side of the upper of a shoe *a* of the wearer, said lever having an inturned lower end 113. In Figure 7 is illustrated a modification of 35 the clasp designated 112. Said clasp has the lever 13 and its inturned end 113. In addition the back or inner jaw 215 of the clasp is formed with a fastener preferably in the form of a stud 312 adapted to enter 40 an eyelet *b* in the upper of the shoe *a* shown in part in said Figure 7. The arrangement illustrated in Figure 7 is intended to effect a more positive engagement of the shoe to withstand at all times the strains of a substantial pull by the ligament on the clasp 45 and shoe.

The belt 10 provides means to hold the upper ends of the ligaments 11 and the clasps 12 or 112 provide for securing it at the lower ends. In addition in order to directionally determine the lifting action or pull exerted by the elements on the foot and lower portions of the legs of the user, I provide leg bands or garters 14 which may be of any approved form having depending 50 tabs 15 provided with hose clasps 16. On the leg bands 14 guide means for the ligaments is provided and in the illustrated example said means consists of a tab 17 depending from the band 14 which tab is also 55 equipped with a hose clasp 16. On the tab 17 is a guide ring 18 secured in the illustrated example by sewing at diametrically opposite sides as at 19. It is to be noted 60 that the guide ring (18) or equivalent guide means is disposed at the back of the leg at 65

the knee. This requires the ligament 11 to take an oblique line from the hip at the outside laterally inward and to the back of the leg.

Reverting to the ligaments 11 the same 70 have incorporated therein elastic or spring means which opposes distention of the ligaments and exerts a lifting action on the foot and lower portions of the legs by the reaction of the elastic sections. I have shown 75 an upper elastic section 20 and a lower elastic section 120, these being connected by an inelastic strip 21 secured at its lower end to the lower elastic section as at 22 and held at its upper end by a suitable buckle 23 permitting adjustment of the inelastic section 21 to vary the total effective length of the ligaments as well as to determine the resistance afforded by the elastic sections to the 80 distention of the ligaments. 85

The clasps 12 or 112 are engaged with the uppers of the shoes *a* at the inner sides. The positioning of the guide means 18 at the back of the leg and the fastening of the ligaments to the shoes and at the inner sides 90 thereof result in an effective resistance by the elastic sections of the ligaments along an oblique line extending from the hip laterally inward to the backs of the legs at the knees and thence downwardly and forwardly to the inner sides of the legs adjacent the ankles. In addition the important 95 result is obtained that the heel automatically lifts in the walking of the user of my leg 100 and foot developer and in order to overcome resistance offered by the ligaments the user is compelled or at least finds it more natural to first bring the heel firmly down and then the toe or ball of the foot to bring about true heel and toe walking and toeing in. The disposition of the ligament elements 11 along the oblique line described minimizes 105 the friction of said elements against the person or garments of the wearer and interferes to the minimum extent with the free movements of said elements. 110

In order to prevent discomfort to the user of the appliance the upper elastic section 20 of each ligament 11 is connected to the belt 10 by a tab 24 to which is secured a loop 25 through which the upper end of the section 20 is passed, said upper end having snap fastener elements as indicated at 26 to detachably hold said elastic section and the ligament to the belt. At the lower end of the tab 24 the same is folded in a manner to provide a pad 27 to cushion the pressure of the section 20 against the hip of the user. Again, at the bottom of the ligament, that is, at the lower end of the elastic section 120, the clasp 12 is shown as connected by a loop 32 with a tab 33 secured to an end of the elastic section 120 and at the juncture of tab 33 with said elastic section 125 the material is formed into a plurality of 130

folds or thicknesses which also constitute a pad 34 to prevent discomfort by lateral pressure of the ligament at the ankle.

It is important to prevent the falling of

- 5 the belt 10 or its displacement about the body of the user of the appliance and therefore I provide effective means for the purpose, said means in Figures 1 and 2 is shown as consisting of a hanger element 28 dou-
 10 bled on itself and secured by its ends to belt 10 at each side of the lacing 110 of the belt. The element 28 is shown as formed with a loop 29 at the top adapted to be en-
 15 gaged with a button 30 on suspenders 31 at the back thereof. Thus, the fastening of the element 28 to the suspenders, in the case of a male wearer of the appliance, will be effective in constraining the belt 10 to main-
 20 tain its position with the ligaments 11 prop-
 25 erly disposed at the sides. For women's wear the belt 10 is equipped with an element 128 corresponding in all respects with the element 28 except that it is provided at the top with a hook 129 to engage corset strings (not shown) at the back of the wearer.

It has been found in practice that the mode of functioning of the above described appliance due to the particular manner of disposing the ligaments 11 running from the hips laterally inward on oblique lines to the backs of the legs at the knees and thence continuing inward to the inner sides of the legs at the ankles requires the muscles of the hips, legs and feet to perform the necessary work and subjects them to benevolent exercising movements in overcoming the resistant attribute in the elements 11, thus effectively making for restorative results in the defective regions.

- 40 In the described assemblage the shoe is employed as a foot sling. In the form shown in Figures 8 to 10, an anklet having a foot strap is employed as a foot sling in association with the ligaments 11. In Figure 8 is shown an anklet 35 usually of canvas suitably reinforced where needed, as by a layer 36 of leather, extending over a suitable area of the anklet. A ring 37 or equivalent device is secured to the anklet 35 at the reinforced area 36 to receive a snaphook 38 or like fastening device on the lower end of the bottom elastic section 120 of ligament 11. The anklet is tightened about the leg of the user by reason of lacing 39 a run of which may be passed through eyelets in the shoe C. On anklet 35 is a stud 40 to pass through the hole c of the shoe. The purpose of the stud 40 and hole c in the shoe or the passing of the anklet lacing through the shoe eyelets is to prevent the possibility of pull on the ligament 11 exerting a force on the anklet tending to displace the same about the leg of the wearer. The numeral 41 indicates a foot strap suspended from the anklet and adapted to be passed beneath the

arch of the foot. Thus, the anklet assemblage constitutes a foot sling in lieu of the shoe a functioning as a foot sling as in Figure 1.

In the form shown in Figure 11 the anklet 135 is shaped with a foot strap so that it presents an opening at the front through which the foot passes, the foot strap portion going beneath the arch of the foot. The ring 137 corresponding with the ring 37 is in the form shown in Figure 11 carried by an auxiliary foot strap 141 and said auxiliary foot strap 141 passes freely through a guide loop 42 on the anklet 135.

In the form shown in Figure 12 illustrating the adaptation of the appliance for juvenile wear, the ligaments 11 are passed through holes d in the stockings D adjacent to the top of the uppers of the shoes A and in that way the clasp is engaged with the shoes without exposing the ligament conspicuously.

I would state in conclusion that while the illustrated examples constitute practical embodiments of my invention, I do not limit myself strictly to the exact details herein illustrated, since, manifestly, the same can be considerably varied without departure from the spirit of the invention as defined in the appended claims.

Having thus described my invention, I claim:

1. In an appliance for use in subjecting legs and feet to corrective treatment, elongated elements adapted to be disposed along the legs of the person to be treated, said elements having embodied therein means yieldingly resistant of distention thereof and adapted to react and restore said elements after distention; together with means to secure said elements at the lower ends adjacent the feet of the user, as well as means to position and hold the upper ends of said elements adjacent the hips, to thus constitute said elements artificial ligaments, and guide means for said elements between said upper and lower ends, and positioned to guide the ligaments to and past the backs of the legs adjacent the knees.

2. In an appliance for use in subjecting the legs and feet to corrective treatment, elongated elements having incorporated therein means yieldingly resistant of distention of the elements and adapted to react and restore the elements after the distention, means from which said elements are pendent, said means adapted to position and hold the upper ends of said elements adjacent the hips of the user, means to fasten said elements at their lower ends adjacent to the feet of the user, and guide means adapted to be applied to the legs of the user above the feet with which guide means said elements have running engagement, said guide means being positioned to cause said

elements to run obliquely from the hips to and past the backs of the legs adjacent the knees.

3. In an appliance for use in subjecting the legs and feet to corrective treatment, elongated elements having incorporated therein means yieldingly resistant of distention of the elements and adapted to react and restore the elements after the distention, a belt from which said elements are pendent in positions at the sides of the belt, so as to be disposed at the hips of the user, means to secure the lower ends of the elements to wearing apparel adjacent the feet and at the inner sides of the legs, and guide means between the belt and the lower ends of said elements and adapted to constrain said elements to take a position extending from the hips downwardly and laterally inward so that the said elements will assume an approximately oblique line from the lower ends at the inside of each foot to the hips.

4. In an appliance for use in subjecting the legs and feet to corrective treatment, elongated elements composed of upper and lower elastic sections and an intermediate inelastic section adjustable to vary the total effective length of said elements and thereby determine the resistance to distention afforded by the said elastic sections, means to position and hold said elements at the upper ends adjacent the hips of the user, means to guide said elements to the backs of the legs adjacent the knees, and means to secure the lower ends to articles of wear of the user adjacent the feet so that the reaction of the said elements after distention will exert a lifting action.

5. An appliance for use in subjecting the legs and feet to corrective treatment, elongated elements composed of upper and lower elastic sections and an intermediate inelastic section adjustable to vary the total effective length of said elements and thereby determine the resistance to distention afforded by the said elastic sections, means to position and hold said elements at the upper ends adjacent the hips of the user, and means to secure the lower ends to articles of wear of the user adjacent the feet so that the reaction of said elements after distention will exert a lifting action; together with guide means adapted to be fixed to the legs of the user above the lower ends of said elements and positioned to guide said elements to the backs of the legs with which guide means said inelastic section of the elements has running engagement.

6. In an appliance for use in subjecting the legs and feet to corrective treatment; elongated elements having incorporated therein means yieldingly resistant of distention and adapted to react and restore said elements after distention, a belt from which said elements are pendent, and pads

disposed adjacent the connection between the belt and said elements to cushion the pressure of said elements; together with means to hold said elements disposed along the legs of the wearer and determinative of the line along which the elements are positioned.

7. An appliance for use in subjecting legs and feet to corrective treatment, said appliance having an elongated element in which is incorporated means yieldingly resistant of distention and adapted to react and exert a lifting action after distention, and means to position said element and hold the same disposed along the leg of the wearer to constitute a ligament between the lower portion of the leg at the inner side and a point adjacent a hip of the user, said second mentioned means including holding means for the upper end of the resistant ligament element as well as means constituting a foot sling with which the lower end of said element has connection; together with means on the foot sling to engage an article of wear and restrain the foot sling against a displacing movement about the leg of the wearer.

8. An appliance for use in subjecting legs and feet to corrective treatment, said appliance having an elongated element in which is incorporated means yieldingly resistant of distention and adapted to react and exert a lifting action after distention, and means at the upper end of said element to position said upper end and hold the same against displacement, an anklet, a foot strap pendent from the ankle adapted to pass beneath the foot of the user, means on said anklet at a side thereof to be engaged by the lower end of said ligament element, and means on the anklet adapted to engage an article of foot wear to prevent displacement of the anklet about the ankle.

9. An appliance for use in subjecting legs and feet to corrective treatment, said appliance having an elongated element in which is incorporated means yieldingly resistant of distention and adapted to react and exert a lifting action after distention, and means to position said element and hold the same disposed along the leg of the wearer to constitute a ligament between the lower portion of the leg and a point adjacent a hip of the user, said second mentioned means including holding means for the upper end of the resistant ligament element as well as means constituting a foot sling with which the lower end of said element has connection, said foot sling comprising an anklet and a foot strap to extend beneath the foot of the user, as well as an auxiliary foot strap having means for connection with said ligament, the auxiliary strap at the end connecting with the ligament being movable relatively to the adjacent anklet surface.

10. An appliance for use in subjecting legs and feet to corrective treatment which comprises elongated elastic ligaments, means for supporting the upper ends of the ligaments adjacent the hips, said ligaments being carried downwardly and diagonally across the back of the legs, and means for securing the lower end of a ligament to the
- 5 foot and at the inside of the foot so that the ligaments will not only raise the foot **10** but by reason of the diagonal disposition of the ligaments and the connection of the ligaments at the inside of the foot, the foot will be toed-in.

JOHN J. COOPER.
